(57) **CLAIM**

I claim the ornamental design for a shackle guard with tether, as shown and described.

DESCRIPTION

FIG. 1 is a front right perspective view of a shackle guard with tether, showing my new design.

FIG. 2 is a front left perspective view of the shackle guard with tether.

FIG. 3 is a left view of the shackle guard with tether.

FIG. 4 is a right view of the shackle guard with tether.

FIG. 5 is a front view of the shackle guard with tether.

FIG. 6 is a rear view of the shackle guard with tether.

FIG. 7 is top view of the shackle guard with tether; and,

FIG. 8 is bottom view of the shackle guard with tether.
